UNITED STATES PATENT OFFICE.

ASAHEL K. EATON, OF BROOKLYN, NEW YORK.

VOLTAIC TRANSMITTING-TELEPHONE.

SPECIFICATION forming part of Letters Patent No. 223,718, dated January 20, 1880.

Application filed November 13, 1879.

To all whom it may concern:

Be it known that I, ASAHEL K. EATON, of Brooklyn, in the county of Kings and State of New York, have invented certain new and useful Improvements in Voltaic Transmitting-Telephones; and I do hereby declare the following to be a full, clear, and exact description of the invention, such as will enable others skilled in the art to which it appertains to make and use the same, reference being had to the accompanying drawings, and to letters of reference marked thereon, which form a part of this specification, in which—

Figure 1 is a vertical central section of the telephone. Fig. 2 is a plan view of the back of the instrument.

My invention relates to the construction of an efficient voltaic transmitting-telephone; and it consists in supporting the differentiating button and connecting it with the contact-pieces by means of a flexible elastic tube, and also in a diaphragm held by central pressure only.

Referring to the drawings, M O O represent the mouth-piece of the telephone, having a vibrating diaphragm, A, of brass, iron, or other suitable material. The diaphragm is held in place by the spring R, which is fastened by the screws K G, and presses upon an elastic circular cushion, H.

E represents a contact-piece of brass faced on the upper end with platinum, and riveted at its lower extremity, I, to the diaphragm.

Above E is a small cylinder or button, C, (the composition of which is given in my patent of May 28, 1879,) or its equivalent, and above this button a contact-piece of brass, D, faced with platinum. The button may be made of solid retort-carbon, if desired, with good results. These three pieces E D C are embraced and connected together by means of a short piece of india-rubber or other elastic tubing, F, the caliber of which is smaller than the diameter of the contact-pieces and button, so that when they are forced into the tube the contact-pieces and button are held as one piece, though not quite touching each other.

Pressing upon the upper end of the contact-piece D is another diaphragm, B, held in place by the spring R, having an intervening elastic cushion, H'.

The spring R can be made to press with more or less force upon the diaphragm B by means of an adjusting-screw, G', and elastic cushion S.

The contact-pieces and button are, by the action of the spring R and of the screw G', caused to touch slightly, so that a battery-current passing through P P finds its way through D C E, and may be varied by the vibration of the diaphragm A, such vibration varying the conductivity of the button C. This transmitter, having two diaphragms, may be converted into a duplex instrument, if desired, by the addition of a second mouth-piece, O M O, represented in dotted lines. On the other hand, the instrument may be simplified by removing the plate B and allowing the spring H to press directly upon the contact-piece D. In that case the wire P' is connected with the spring R'; but I do not intend to claim this second plate or any of its adjuncts as part of the subject-matter of this specification, though I may make it the subject of an application for a separate patent.

By the foregoing description it will be seen that there are here two contact-pieces and a solid resistance-piece, all inclosed and supported by an elastic tube that embraces them tightly enough to hold them in position, and yet keep them from absolute contact with each other. By these means the button and contact-pieces, though solid in themselves, are yet elastic as a whole, and the harshness of articulation caused by the friction involved in the use of solid supports is avoided.

It will be observed that if these solid contact-pieces and the solid button be put into a hard non-elastic tube to make them work they would have to be put in loosely, which, in their operation, would cause a harsh jarring sound that would confuse the articulation, to avoid which the elastic tube is employed as a supporter.

The diaphragm-plate A, instead of being held or secured at its periphery, is secured or held by a fastening applied to its center.

In the drawings there is a spring, R, reaching across the plate, that bears upon an elastic cushion set on the center of the plate around the bottom end of the contact-piece E, which is riveted to the center of the plate. By these

means the plate, instead of being clamped at its periphery, is clamped or held at its center, leaving it entirely free to vibrate uniformly from center to circumference on all sides, and 5 to expand and contract without distortion; but I do not claim, broadly, the use of a spring for holding the diaphragm in place.

I do not claim a spring forming or carrying one electrode of the circuit of the telephone, 10 and constantly pressing against the other electrode and the diaphragm, to maintain the required initial pressure between the electrodes.

Having described my invention, I claim—

1. The combination of the contact-pieces and

solid resistance-piece in a flexible elastic tube, 15 for the purpose of remedying the harshness of articulation caused by the friction involved in the use of non-elastic supports.

2. In a voltaic telephone, a diaphragm held in place by central pressure only, thus leaving 20 the edges free, substantially as set forth.

In testimony that I claim the foregoing I have hereunto set my hand this 13th day of November, 1879.

ASAHEL K. EATON.
